(57) **CLAIM**

The ornamental design for a combined blood pressure detector and detector holder, as shown and described.

DESCRIPTION

FIG. 1 is a front perspective view of a blood pressure detector showing our design.

FIG. 2 is a bottom rear perspective view of the blood pressure detector.

FIG. 3 is a front elevation view of the blood pressure detector.

FIG. 4 is a rear elevation view of the blood pressure detector.

FIG. 5 is a left side elevation view of the blood pressure detector.

FIG. 6 is a right side elevation view of the blood pressure detector.

FIG. 7 is a top plan view of the blood pressure detector.

FIG. 8 is a bottom plan view of the blood pressure detector.

FIG. 9 is a front perspective view of a detector holder showing our design.

FIG. 10 is a bottom rear perspective view of the detector holder.

FIG. 11 is a front elevation view of the detector holder.

FIG. 12 is a rear elevation view of the detector holder.

FIG. 13 is a left side elevation view of the detector holder.

FIG. 14 is a right side elevation view of the detector holder.

FIG. 15 is a top plan view of the detector holder.

FIG. 16 is a bottom plan view of the detector holder.

FIG. 17 is a front, top, and right side perspective view of a combination of the blood pressure detector shown in FIGS. 1-8 and the detector holder shown in FIGS. 9-16, wherein the blood pressure detector is attached to the detector holder.

FIG. 18 is a rear, bottom, and left side perspective view of the combination of the blood pressure detector and the detector holder.

FIG. 19 is a front elevation view of the combination of the blood pressure detector and the detector holder.

FIG. 20 is a rear elevation view of the combination of the blood pressure detector and the detector holder.

(Continued)

FIG. 21 is a left side elevation view of the combination of the blood pressure detector and the detector holder.
 FIG. 22 is a right side elevation view of the combination of the blood pressure detector and the detector holder.
 FIG. 23 is a top plan view of the combination of the blood pressure detector and the detector holder; and,
 FIG. 24 is a bottom plan view of the combination of the blood pressure detector and the detector holder.
